UNITED STATES PATENT OFFICE.

HERBERT A. DENT, OF CHICAGO, ILLINOIS, ASSIGNOR TO DENT AUTO EQUIPMENT COMPANY, OF CHICAGO, ILLINOIS, A CORPORATION OF ILLINOIS.

DESIGN FOR AN AUTOMOBILE RADIATOR CAP.

Application filed November 27, 1922. Serial No. 4,413. Term of patent 14 years.

To all whom it may concern:

Be it known that I, HERBERT A. DENT, a citizen of the United States, residing at Chicago, in the county of Cook and State of Illinois, have invented a new, original, and ornamental Design for Automobile Radiator Caps, of which the following is a specification, reference being had to the accompanying drawing, forming part thereof.

In the drawing Fig. 1 is a front view of a radiator cap made in accordance with the design of my invention; and Fig. 2 is a side view thereof.

I claim:

The ornamental design for an automobile radiator cap, as shown.

HERBERT A. DENT.
